UNITED STATES PATENT OFFICE

DAVID E. SKIRVIN, OF JUNCTION CITY, OREGON, ASSIGNOR OF ONE-HALF TO THOMAS J. SKIRVIN, OF EUGENE, OREGON

MOLASSES-FEED MIXER

Application filed August 13, 1929. Serial No. 385,484.

This invention relates to devices whereby molasses in a cold condition can be mixed with and into grain which has been ground to the consistency of flour, and the general object of this invention is to provide a mechanism of this character so constructed that molasses in the form of a spray will be mixed with the ground grain also in the form of a spray as it may be termed, and a further object is to provide means for this purpose which is so designed that a predetermined amount of molasses may be mixed with a predetermined amount of grain so that in the mixture, the grain and the molasses will have certain proportions.

A further object is to provide a construction of this character which includes means for throwing the grain centrifugally outward and forward and means for spraying the molasses on to this grain as it is so thrown and a further object is to provide a machine of this character in which a tank is used for holding the grain and wherein the tank is moved backward and forward preferably automatically, causing the mixing paddles to mix the grain from one end of the tank to the other.

Other objects will appear in the course of the following description.

My invention is illustrated in the accompanying drawings, wherein:—

Figure 1 is a longitudinal sectional view through a molasses mixer constructed in accordance with my invention.

Figure 2 is a section on the line 2—2 of Figure 1.

Referring to these drawings, 10 designates a tank which may be made of metal or other suitable material, which tank is mounted upon the wheels 11 running on tracks 12, the tracks 12 having a length approximately equal to twice the length of the tank 10. Supports 13 of any suitable character support a shaft 14 which extends longitudinally through the tank and with which the tank has sliding engagement.

Disposed upon the middle of this shaft, for instance, is a cylindrical hub 15 and disposed on each side of this hub are disks 16 which carry upon their peripheries the vanes

or blades 17 which will be later adverted to. Mounted upon the top of the tank is a supporting frame 18 which carries a hopper or like molasses reservoir 19 from which a pipe 20 extends downward and discharges against the face of the middle portion of the hub 15, the lower end of the pipe being spaced from this hub any suitable distance.

The tube 20 discharges the molasses against the hub 15 which is rotating at a high rate of speed and the rotating hub throws the molasses off outward by centrifugal force in the form of a more or less fine spray toward the circumferential wall of the tank.

Disposed at the peripheries of the disks as previously stated or adjacent thereto are the paddles, vanes or blades 17. These have straight shanks which may be attached to the disks 16 and the paddles or vanes are twisted at an angle to the plane of the disk 16 or in the manner of fan blades or propeller blades.

In the use of this mechanism, the grain to a predetermined amount is filled in to one end of the tank 10, the tank having a lid 22 at the top for this purpose and having an opening, at for instance, the right hand end of the tank, at its bottom for the purpose of discharging the mixed grain and molasses.

When the grain has been disposed within the left hand end of the tank in Figure 1 and cold molasses disposed within the hopper or reservoir 19, the shaft is rotated by a motor or other suitable mechanism at a high speed while at the same time the tank is slowly pushed toward the right on its wheels 11, thereby bringing the feed in contact with the paddles or vanes 17, which, by their being angled, throw the feed in a spray toward the right. The feed or grain passes between the edges of the disks 16 and the wall of the tank and at this point the grain or feed comes in contact with the spray of molasses that is being thrown out from the hub 15. The paddles or vanes 17 throw the feed with such force that it is thrown to the right hand of the tank and there piles up while the tank is gradually pushed to the right. Eventually all of the feed will have been fed to the left hand end of the tank through the spray of molasses and into the right hand end of

the tank.

Disposed upon the middle of this shaft, for instance, is a cylindrical hub 15 and disposed on each side of this hub are disks 16 which carry upon their peripheries the vanes

the tank. When the tank has been shifted to its full extent to the right, the paddles, disks and the molasses discharge pipe are at the left hand end of the tank.

Then if it be desired to continue the mixing without mixing any more molasses, the supply of molasses is cut off and the disks and paddles are reversely rotated to throw the feed from the right hand end of the tank to the left hand end of the tank and more thoroughly mix the feed with the molasses or a further amount of molasses may be discharged through the molasses supply pipe against the hopper and the grain still further mixed with molasses until precisely the proper proportion of molasses and grain has been secured. Thus it will be obvious that the tank may be shifted backward and forward a number of times and each time an additional amount of molasses may be sprayed into the grain.

It will be understood that the molasses used is thick and gummy and, therefore, it is necessary to convert it into a relatively fine spray by causing the molasses to flow upon the revolving hub. This hub in actual practice is about six inches in diameter and a small stream of molasses coming in contact with the hub is thrown off from the hub in the form of a very fine spray. The purpose of the two disks 16 is to protect the hub and prevent the grain coming in contact with the molasses at the point where it hits the hub and before it is thrown from the hub in the form of a spray. The molasses is protected from contact with the grain by flowing through the pipe 20. The tank, it will be understood, is only a means of causing the grain to come in contact with this fine spray of molasses but the tank is necessary as it is the only means which will hold a specified amount of grain so that a specified amount of molasses can be mixed in with a specified amount of grain. Thus I have provided a machine which will thoroughly mix a predetermined and certain amount of molasses into a predetermined and certain amount of feed. In other words, I have provided a batch molasses mixer.

It is within the purview of my invention to mix molasses with any kind of feed which is passing through or is confined within any kind of a drum or tank that has within it fast revolving blades and which is provided with means whereby the molasses may be thrown off in the form of a relatively fine spray through which the grain is caused to pass. The molasses may thus be mixed into ground grain or any other relatively fine or comminuted material to which the molasses will stick if the grain and the molasses are separately reduced to a spray and then thrown together in mid air. My tank or drum is designed to hold several hundred pounds of grain or meal. It is further so

designed that different kinds of grain or ground meal may be disposed within the mixing drum or tank and these several kinds of meal or grain thoroughly mixed together and at the same time mixed with molasses.

It is obvious that the motion of the rotatable blades may be reversed by reversing the motor used for driving the shaft 14 or by any reversing mechanism and then, after the tank or drum has been pushed sufficiently far to the right the tank motion of the blades may be reversed and the tank then pushed from the right toward the left. I have not illustrated any reversing mechanism because such reversal involves merely the reversal of the motor or the use of reversing gears which is an obvious construction.

While I have illustrated certain details of construction and arrangements of parts, I do not wish to be limited thereto as obviously these might be varied in many ways without departing from the spirit of the invention as defined in the appended claims.

While I have shown a hand operated valve for controlling the passage of molasses, it is to be understood, that I may provide a valve which will shut off when the tank has moved to the end of its stroke in one direction. Nor do I wish to be limited to the exact form of blades whereby the grain is thrown through the spray of molasses; nor to the exact construction of the movable tank and the outer casing as these parts might be varied without departing from the spirit of the invention.

I claim:—

1. A mixing device of the character stated comprising a tank, a shaft extending longitudinally through the tank and having means whereby it may be rotated at a high speed, means for conducting molasses to a point contiguous to the shaft, and discharging molasses upon this shaft to thereby cause the shaft to throw the molasses outward in the form of a spray, and means exterior of the point of discharge of the molasses upon the shaft for discharging the material to be mixed with said molasses from one end of the tank toward the other end of the tank through said spray.

2. A mixing device of the character stated comprising a tank, a shaft extending longitudinally through the tank and having means whereby it may be rotated at a high speed, means for conducting the molasses to a point contiguous to the shaft and discharging the molasses upon this shaft to thereby cause the shaft to throw the molasses outward in the form of a spray, and means disposed outward of the point of discharge of the molasses on the shaft for discharging the material to be mixed with said molasses from one end of the tank toward the other end of the tank through said spray and including blades rotatable with said shaft.

3. A mixing device of the character stated

comprising a tank, a shaft extending longitudinally through the tank and having means whereby it may be rotated at a high speed, a pipe leading to a point contiguous to the shaft and discharging molasses upon this shaft to thereby cause the shaft to throw the molasses outward in the form of a spray, and means for discharging the material to be mixed with said molasses from one end of the tank toward the other end of the tank through said spray, including a pair of disks disposed on each side of the molasses discharging means and blades disposed at the circumference of said disks and formed to cause the material in one end of the tank to be discharged longitudinally through the tank toward the other end exteriorly of said disks and through the spray of molasses; the molasses discharging pipe having its discharge 20 opening disposed inward of the peripheries of said disks.

4. A mixing device of the character stated comprising a tank, a shaft passing through the tank and having means whereby it may be revolved at a high speed, means including a tube extending nearly to the shaft by which to discharge molasses on to the rapidly rotating shaft to cause the molasses to be discharged outward and form a spray, disks 25 mounted upon the shaft on each side of the molasses discharging tube, the discharge end of the tube being disposed inward of the peripheries of the disks, blades rotatable with the shaft and disposed outward of the disks 30 and formed to engage material in one end of the tank and discharge the material longitudinally outward of the disks and through said spray, the tank and shaft, its disks, blades and the molasses tube being relatively 35 movable longitudinally.

5. A mechanism of the character described comprising a tank having supporting means whereby it may be longitudinally shifted to a predetermined extent, a shaft passing longitudinally through said tank, a shaft having means whereby it may be driven at a high speed, the tank being longitudinally shiftable upon the shaft, a pair of rotatable mixing blades mounted upon the shaft, and means 45 for discharging molasses upon the rapidly revolving shaft between said mixing blades whereby to cause the molasses to be discharged outward against the material acted upon by said blades.

55 6. A mechanism of the character described, comprising a tank, adapted to contain material at one end, a shaft extending longitudinally through the tank and having means whereby it may be rotated at a high speed, the tank being movable longitudinally with 60 relation to the shaft, blades mounted upon the shaft and formed to engage the material at one end of the tank and throw the material longitudinally toward the other end of the 65 tank as the tank is being moved relative to

the shaft, and means for spraying molasses upon said material as it is acted upon by the blades.

7. A mechanism of the character described including a tank adapted to contain granular material, means within and intermediate the ends of the tank for taking up said granular material from one end of the tank and spraying it toward the other end of the tank, means for relatively shifting the spraying means and the tank longitudinally of the tank as the material is taken from one end of the tank and deposited in the other end thereof, and means for spraying liquid into the material in a direction at right angles to the direction of movement of the material as it is being sprayed.

In testimony whereof I hereunto affix my signature.
